UNITED STATES PATENT OFFICE

ALBERT D. SILVA, OF PHILADELPHIA, PENNSYLVANIA, ASSIGNOR TO ATWATER KENT MANUFACTURING COMPANY, OF PHILADELPHIA, PENNSYLVANIA, A CORPORATION OF PENNSYLVANIA

AMPLIFYING SYSTEM

Original application filed May 10, 1929, Serial No. 361,910. Divided and this application filed February 25, 1931. Serial No. 518,097.

My invention relates to radio receiving apparatus or the like, utilizing thermionic tubes supplied from a source of fluctuating current, as for example, from a rectifier system through a filter comprising a suitable combination of impedances.

In accordance with my invention, the field winding of an electro-dynamic speaker is included in circuit in the negative conductor of an electrode current supply and all or any suitable portion of the drop of potential across the field winding is utilized to bias grid structure of one or more tubes, particularly power amplifier tubes requiring high magnitude of biasing potential; and more specifically the field winding is included in the negative side or conductor of an alternating current rectifying and filter system, either external to the filter system, or, and preferably, within the filter system to serve as an impedance thereof.

This application is a division from my application Serial No. 361,910, filed May 10, 1929.

For an understanding of my invention, reference is to be had to the accompanying drawings, in which:

Fig. 1 diagrammatically illustrates a radio receiving system embodying the invention.

Fig. 2 is a schematic diagram of a part of a system showing a modified form of my invention.

Fig. 3 illustrates a further modification.

In the anode or output circuit of the tube V is included the primary P of a transformer T whose secondary S is connected to the grids g of the amplifier tubes V1, V2 connected in push-pull relation. The primary P1 of the transformer T1 is connected at its outer terminals to the anodes a of the tubes V1, V2, and is inductively related to the secondary S1 of the transformer which is connected to the movable coil M of an electrodynamic speaker having a diaphragm D actuated by the coil

M. The condenser K connected between the anodes a of tubes V1, V2 cooperates with transformer T1 and coil C to reduce in amplitude or to cut off objectionable high pitched noises attendant to high amplification, particularly when an electrodynamic

speaker is utilized as a sound reproducer. The capacity of the condenser may be for example of the order of .02 mfd.

The input circuit of the tube V may be associated with the output circuit of a detector, preferably preceded by one or more radio frequency amplifier stages to constitute radio receiving apparatus, or of an audio amplifier tube preceded by a detector and radio frequency amplifier stages, or the input circuit of the tube V may include phonographic pick-up device.

In Fig. 1, the tube V amplifies at radio frequency and is coupled to the anode circuit of the detector tube V4 by resistance T3 and condenser C5. Preferably between the input circuit of the detector and an antenna path, or absorption loop, there may be interposed one or more stages of radio frequency amplification.

The input circuit of the screen-grid amplifier tube V5, preferably tuned, is directly associated with the absorption path or there may be interposed one or more additional stages of radio frequency amplification, and its anode circuit is coupled to the input circuit of the detector V4 by transformer T5. The input circuit of the tube V4 is preferably tuned, as by variable condenser K1.

The tubes V4 and V5 are provided with heaters h traversed by current supplied from the secondary S4 of a power supply transformer T2 to raise the temperature of the uni-potential cathodes u to effect emission of electrons. The cathodes f of the tubes V1 and V2 are connected to the secondary S5 of the power transformer. If desired the tube V5 and other radio frequency amplifier tubes may be of the three-electrode type and utilizing a heavy filament, instead of a heater and a uni-potential cathode, in which event they are connected in a manner similar to tube V4, for example.

The audio frequency variations of current in the primary P of the tube V act upon the secondary S cumulatively to affect the potential of the grids g of the tubes V1, V2, i. e., the grids are of opposite instantaneous polarities. The amplified current variations in the primary P1 of the output transformer T1

are impressed upon the secondary S1 thereof and traverse the movable coil M disposed in the magnetic field of winding F to effect reproduction of sound.

- 5 The primary P2 of transformer T2 supplying current to the several electrode circuits of the thermionic tubes is adapted to be energized from any suitable source, as from line conductors for current of ordinary commercial frequency, by insertion of plug 1 into a socket receptacle or the like, not shown. The terminals of the transformer secondary S2 are connected to a suitable rectifier, specifically to the anodes *a* of the full wave rectifier tube V3 whose filament or cathode *f* is heated by current supplied from the secondary S3 of transformer T2.

10 The negative conductor 4 of the rectifier system is connected to a midpoint of the split secondary S2 and the positive conductor 5 is connected to the cathode *f* of the rectifier tube.

15 The rectified current is smoothed by a filter network comprised by the inductances L1, L2, field coil F of the dynamic speaker and condensers C1, C2 and C3. While a two section filter is shown, insofar as certain aspects of my invention are concerned a smaller or greater number of filter sections may be utilized. The field coil F of the speaker, being of large inductance, is effective as a filter choke and replaces an impedance having solely that function. The anode of the tube V, and of the preceding tubes including radio frequency amplifier tubes of the specific arrangement shown, is connected to the terminal of inductance L2 remote from the rectifier V3, that is, to point *p* of the filter network, and the anodes *a*, *a*, of the tubes V1, V2 are connected to a point *p*1 of the filter network intermediate the inductances L, L2. The potential of the point *p*1 is substantially greater than that of the point *p* because of the high direct current resistance of the inductance L2. The potential applied to the anodes *a*, *a*, of the power tubes V1, V2, is therefore suitably high, without subjecting the rectifier to high voltages. Although the potential of point *p*1 varies somewhat more than that of the point *p* of the filter, nevertheless as the tubes V1, V2 are not followed by a subsequent stage or stages of audio amplification, the hum of line frequency or a multiple thereof reproduced by the loud speaker is not noticeably or appreciably increased. Additionally as the field winding is in the second filter section, there is negligibly small difference of alternating potential of the frequency (or multiple thereof) of the power supply across its terminals.

20 Further in the push-pull arrangement shown as the connection from the point *p*1 is to a midpoint of the primary P1 the periodic variations of supply current are differential

in their effect upon the secondary S1, and balance out.

25 Hitherto and particularly in apparatus in which the tubes were supplied from alternating current, grid biasing potential has been commonly produced by utilizing the voltage drop across resistance traversed by the anode current. This arrangement reduces the voltage at the anode of the tube and is uneconomical and impractical with power tubes receiving high negative bias, because of excessive demand upon the rectifier and/or filter system.

30 In accordance with one aspect of my invention the field winding F of the dynamic speaker included in the negative conductor 4 of the power supply is traversed by the total anode current of all tubes and a whole or a part of the drop of potential across the winding is utilized to bias the grids *g* of the tubes V, V1, V2, V4 and V5. The direct current resistance of the field winding is of such value that for normal demand upon the rectifier filter system, the voltage drop across the winding is equal to or in excess of the required grid bias for the power tubes V1, V2, for example the total drop may be in excess of 100 volts. Preferably as shown there is a conductive impedance R, specifically a resistor, of suitably high magnitude of resistance as for example 17,500 ohms connected in shunt to the field coil F. The use of the potentiometer resistance R, or equivalent, avoids the necessity of tapping the winding F, (Fig. 2) although it will be understood my invention is not limited to the use of resistance R. The impedances of the field winding F and of the resistance R should be so proportioned that the filtering action of the field winding F is not seriously impaired. For example, the value of resistance above given is suitable for a speaker having an impedance of 6000 ohms at 60 cycles and direct current resistance of about 1100 ohms. The potentiometer arrangement has the advantage of insuring good reproduction in the event of heavy signals and consequent flow of grid current.

35 A conductor 6 is connected between the midpoint of the secondary S of the input transformer T of the push-pull stage and a suitable point on the potentiometer resistance R. As the type tubes utilized in the specific circuit shown, are used with a 50 volt grid bias, the grid connection 6 is to a point approximately somewhat less than half way across R from its more positive end, that is the grounded terminal. For other types of power tubes, or for other tubes of the same apparatus, connections from the grids may be made to resistance R intermediate its ends, or to its terminals to points of potentials corresponding to the desired biases. Furthermore the potential drop may be utilized for other purposes, for example, in the auto- 40

matic control of volume of reproduction as in Schade application, Serial No. 384,612, filed August 9, 1929.

The biasing voltage for tubes V, V4, and V5 is obtained by disposing the resistances r, r1, r2, in their respective direct current anode paths between the cathodes u and earth E, the by-pass condensers K2 providing shunt paths for currents of radio and/or audio frequency. As the grid biasing voltages are small compared to that required for the tubes V1 and V2, it may be obtained without serious reduction of anode voltage by this known arrangement above referred to. The power tubes V1, V2 are operated at much higher plate voltages and require grid biasing potentials many times larger than that suitable for the tubes V, etc. In the arrangement described the grid biasing potential and plate current for the tubes V1, V2 are economically obtained, as the voltage drop across a rearranged filter inductance, specifically field winding F is utilized for grid-biasing purposes, thus making available a greater output, or the same output with reduced input, smaller transformers, etc. The arrangement shown and described has resulted in an increase of as much as 25% in the effective output of the rectifier-filter system.

In radio receiving apparatus utilizing the arrangement thus far described, within a short time after closing of switch 2 effecting supply of power to the electrode circuits of the tubes, there is experienced a transient, disagreeable squawk. It was finally determined that the temporary but obnoxious disturbance resulted from the unequal rates of impedance of the tubes V1, V2 as their respective filaments approached operating temperature, and/or because of the connection from the point p1 of the filter to the anodes a of the tubes V1, V2. This troublesome effect was overcome by connecting the condenser C4 of suitable capacity, for example .1 mfd across the connections to the input electrodes of the tubes, that is in shunt to the portion of the resistance R common to the anode and grid circuits of the tubes V1 and V2.

The amplitude of reproduction may be controlled by adjustment of contact s along the potentiometer resistance R3 connected between positive terminal p of the filter and ground to vary the potential of the screen grid sg of the amplifier tube V5.

Referring to Fig. 2, the field winding F is outside of the filter network, but is included in the negative conductor 4 that the high drop of potential across it may be utilized to bias the grids of tubes of associated apparatus. If the source of current delivers pure direct current, as for example when a battery either primary or secondary in char-

acter is used, the filter impedances may be entirely omitted.

In the modification of my invention shown in Fig. 3, the grid biasing resistances r, r1 and r2 are dispensed with and connection is made from the respective cathodes u to suitable points on the several potentiometer resistances R1, R2, etc. connected in shunt to resistance R and field winding F. It will be understood that this shunt arrangement may also be utilized when the field winding F is outside of the filter, if used, as in the modification of Fig. 2.

In another aspect of my invention, by disposition of the field winding F of the speaker in the negative conductor of the anode supply circuit, there is relatively low difference of potential between the speaker and ground which avoids the possibility, for example, of dangerous shocks in the event of connection between the winding F and metallic housing structure of the speaker. Further to increase the factor of safety, the circuit including the secondary S1 of transformer T1 and the movable coil M may be grounded as indicated.

What I claim is:

1. A system comprising an electrodynamic speaker having a movable coil and a field winding, a thermionic tube, means to effect flow of current in a path including said field winding and tube electrode structure in series, a conductive impedance of high resistance in shunt to said winding, and connections from tube input electrodes to points, at least one of which is intermediate the terminals of said impedance, between which exists difference of potential resulting from flow of current through said field winding.

2. Radio receiving apparatus comprising cascaded thermionic tubes, one of which amplifies at radio frequencies and one of which amplifies at audio frequencies, an electrodynamic speaker having a movable coil traversed by currents of audio frequency and a field winding energized by direct current traversing electrode circuits of said tubes, and conductive impedance of high resistance in shunt to said field winding, a connection from one terminal of said field winding to cathode structure of said tubes, and connections from the grids of said tubes to points of said impedance of potential suitably differing in polarity and magnitude from the potential of said terminal.

3. A system comprising a thermionic tube and an electrodynamic speaker having a movable coil and a field winding, a current source for tube electrode structure comprising a filter network including said field winding wholly in the negative conductor thereof, a connection from tube cathode structure to a point in said filter network, and a connection from the grid structure of said tube to a second point in said network more negative than

said first point and having a potential intermediate the potentials of the terminals of said winding.

4. A system comprising an electrodynamic speaker having a movable coil and a field winding, a power amplifier tube requiring high grid bias, a current source for tube electrode structure comprising a filter network including all of said field winding in the negative conductor thereof, and connections from tube input electrodes to points in the filter network of substantial potential difference derived from and less than the drop of potential across said field winding.
5. A system comprising an electro-dynamic speaker having a movable coil and a field winding, a thermionic tube, a current source for tube electrode structure comprising a filter network including said field winding, a conductive impedance of high resistance in shunt to said field winding, a connection from tube cathode structure to a point of said impedance, and a connection from tube grid structure to a second point of said impedance more negative than said first point.

6. A system comprising an electrodynamic speaker having a movable coil and a field winding, a thermionic tube, a current source for tube electrode structure comprising a filter network including said field winding, a resistor in shunt to said field winding, a connection from tube cathode structure to a terminal of said field winding, and a connection from tube grid structure to an intermediate point of said resistor.

7. A system comprising an electrodynamic speaker having a movable coil and a field winding, cascaded thermionic tubes including a power amplifier tube, a current source for tube electrode structure, a multi-section filter including serially connected conductive impedances in the positive conductor and said field winding in the negative conductor, a connection to power amplifier anode structure from a point between serially connected impedances, a connection to anode structure of another said tubes from the output terminal of said filter, connections between power amplifier input electrodes and points in the filter of potential difference derived from and less than the drop of potential across said field winding, and a by-pass condenser connected between said connections.

8. A system comprising an electrodynamic speaker having a movable coil and a field winding, cascaded thermionic tubes including a power amplifier tube, a current source for tube electrode structure, a multi-section filter including serially connected conductive impedances in the positive conductor and said field winding in the negative conductor, a connection to power amplifier anode structure from a point between serially connected impedances, a connection to anode structure of another of said tubes from the output ter-

minal of said filter, a potentiometer resistance in shunt to said field winding, connections between power amplifier input-electrodes and points of said resistance of substantially different potential, and a by-pass condenser connected between said last named connections.

9. A system comprising an electrodynamic speaker having a movable coil and a field winding, a push-pull audio amplifier utilizing thermionic tubes and including said movable coil in the output circuit thereof, a current source for tube electrode structure, a filter network including said field winding in the negative conductor thereof, a potentiometer impedance in shunt to said field winding, and connections from the grids and cathodes of said tubes to points of said impedance between which there exists difference of potential resulting from flow of current through said field winding.

10. A system comprising an electrodynamic speaker having a movable coil and a field winding, a push-pull audio amplifier utilizing thermionic tubes and including said movable coil in the output circuit thereof, a current source for tube electrode structure, a filter network including said field winding in the negative conductor thereof, a potentiometer impedance in shunt to said field winding, connections from the grids and cathodes of said tubes to points of said impedance between which there exists difference of potential resulting from flow of current through said field winding, and a by-pass condenser between said connections.

11. A system comprising thermionic tubes, a current source therefor, a multi-section filter associated therewith, a conductive impedance in the negative conductor of a filter section remote from said current source, and connections from tube input electrodes to points in the filter network of potential difference derived from and less than the drop of potential across said conductive impedance.

12. A system comprising a thermionic tube having an anode, a cathode and a control electrode, a speaker having a field winding, a source of current for the anode circuit of said tube, said field winding traversed by the current in said anode circuit from said source, a conductive impedance in shunt with said field winding, and connections from said control electrode and said cathode to points, one of which is intermediate the terminals of said impedance, between which exists a substantial difference of potential.

13. The combination with a system comprising a thermionic tube having an anode, a cathode and a control electrode, a source of uni-directional current for the anode circuit of said tube, a field winding of a speaker traversed by current in said anode circuit from said source, of means for biasing the

control electrode of said tube negatively with respect to its cathode comprising a conductive impedance in shunt with said field winding, and connections from said control electrode and cathode to points between which exists a substantial difference of potential, one of said points disposed intermediate the terminals of said impedance.

14. A system comprising cascaded thermionic tubes, one of which amplifies at radio frequency and another of which amplifies at audio frequency, an electrodynamic speaker having a field winding traversed by direct current traversing the anode circuits of said tubes, a plurality of impedances in shunt to said field winding, and connections from points intermediate terminals of said impedances to grids of different tubes, said points being more negative than said cathodes, and the potential difference between said points and said cathodes being less than the total fall of potential across said field winding.
